H. S. D. ATTORNEY

UNITED STATES PATENT OFFICE.

CHARLES H. CUNO, OF MERIDEN, CONNECTICUT, ASSIGNOR TO THE CUNO ENGINEERING CORPORATION, OF MERIDEN, CONNECTICUT, A CORPORATION OF CONNECTICUT.

CIGAR LIGHTER.

Application filed December 11, 1924. Serial No. 755,169.

My invention relates particularly to the casing and method of mounting it, particularly on the instrument board of an automobile.

5 The main object is to provide a simple and inexpensive construction which may be readily attached to the dash board or instrument board without cutting or drilling any holes, or marring the board.

10 To accomplish this object I provide the reel casing with an opening and seat for the holder of the igniter, and a bracket or clamping frame which is secured to the casing immediately above the holder. This bracket is provided with set screws in the rear so that the device may be readily attached or detached.

15 Figure 1 is a perspective view of a construction embodying one form of the improvements of my invention.

20 Figure 2 is a side view and partial section showing the device attached to an instrument board.

25 Figure 3 is a detail plan view of the clamping bracket.

The casing 5 may be of any suitable construction and provided with any suitable form of spring reel or drum 6. The front 7 of the casing is provided with an opening 8 for the cord and a seat 9 for the holder 10.

30 This holder may be provided with any suitable form of igniter or lamp and may also have a switch with an operating button 11. This opening 8 is arranged in such position with respect to the reel as to permit the conductor cable or cord to be drawn out readily.

35 The bracket is preferably of sheet metal of U shaped section and provided with a back arm 12, a horizontal extension 13, and an outer arm 14. The back arm may be suitably secured to the casing above the seat 9, as for instance, by welding or riveting. This back arm or base is provided with lugs 15 which extend out beyond the sides of the casing. A set screw 16 is adjustably carried in each of these lugs so that the device may be clamped to the lower edge of an instrument board or dash 17.

40 The device is adapted to be attached to any form of board. In the form shown the board is of sheet metal and has a channelled flange 18 at its lower edge. Preferably the screws 16 are inclined downwardly and con-

verged forwardly. This simple expedient 55 insures a more secure hold on the board. It provides a maximum security in compact arrangement. This angular arrangement of the screws may be readily provided by simply bending the lugs 15 slightly at the points 60 where they join the arm 12.

By mounting the holder 10 in the lower edge of the casing beneath the instrument board the device is not only less obtrusive to view but out of the way and protected 65 against injury. This construction is also much less expensive to make than those of the prior art with which I am familiar in which there has always been a long tubular extension for the holder with clamp nuts. 70 This arrangement in which the holder is almost entirely beneath the instrument board also protects the switch button 11 from accidental contact.

75 This construction does away entirely with the necessity of drilling or boing holes in the instrument board. It also makes it possible to readily remove the cigar lighter or to change its position to suit the convenience of the user.

80 It should be understood, of course, that the invention is also applicable to trouble lamps, such as shown in Cuno Patent No. 1,208,504, and to cigar lighters having automatic switches, such as shown in Cuno 85 Patents Nos. 1,342,015, 1,355,943, 1,378,013, or manually operable switches in the casing, as in Cuno Patent No. 1,422,180.

85 In my former application 714,314, I have shown a form of construction in which I 90 have broadly claimed the combination of a reel casing with a tubular extension for the cigar lighter holder and a clamping frame detachably mounted on this extension.

I claim:

95 1. A supporting clamp bracket having a shelf with a front arm and a rear arm secured thereto, said rear arm having ears extending from its opposite sides, said ears being inclined with respect to each other and with respect to the front arm, and set screws passing forwardly through said ears and converging toward each other and toward said shelf.

100 2. A U-shaped supporting clamp bracket for the purpose specified having front and rear members, and two set screws passing forwardly through the rear member, in-

clined toward each other and inclined downwardly toward the front member.

3. A reel casing having a cable passage in its lower front edge, a channel-like supporting clamp bracket secured to said casing and having front and rear flanges above said cable passage and set screws passing forwardly through said rear flange one being on each side of the reel casing, said screws being inside of the reel casing, said screws being inclined forwardly and downwardly toward each other and toward the front flange.

4. A sheet metal supporting clamp bracket having a horizontal shelf with an upwardly

projecting front arm and a rear arm, said front arm being adapted to engage the front of an instrument board and said rear arm being adapted to be attached to the casing of a cigar lighter reel, and oppositely disposed clamp screws passing forwardly thru opposite sides of said rear arm and spaced apart from each other, and extending forwardly towards said front arm, said screws being in a plane which makes an obtuse angle with respect to said front arm on the side adjacent said shelf. 15 20

CHARLES H. CUNO.
